UNITED STATES PATENT OFFICE.

OSCAR MARSCHUETZ, OF LOUISVILLE, KENTUCKY, ASSIGNOR TO THE
AHRENS & OTT MANUFACTURING COMPANY, OF SAME PLACE.

DESIGN FOR A BATH-TUB.

SPECIFICATION forming part of Design No. 24,777, dated October 22, 1895.

Application filed May 7, 1895. Serial No. 548,448. Term of patent 7 years.

To all whom it may concern:

Be it known that I, OSCAR MARSCHUETZ, a citizen of the United States, residing at Louisville, in the county of Jefferson and State of Kentucky, have invented and produced a new and original Design for Bath-Tubs, of which the following is a specification, reference being had to the accompanying drawings, showing a part hereof.

- Figure 1 is a perspective view of a bath-tub, showing my design. Fig. 2 is a plan view thereof. Fig. 3 is a vertical transverse sectional view on the plane indicated by the dotted line $x x$ of Fig. 2. Fig. 4 is a vertical transverse sectional view on the plane indicated by the dotted line $y y$ of Fig. 2. Fig. 5 is a transverse sectional view, on an enlarged scale, through the roll-rim and the depression therein.
  - My invention is a design for a bath-tub, the leading features of which consist, first, of a roll-rim having the contour or configuration shown; secondly, in the pattern upon the outer wall of the tub, and, thirdly, in the leg shown and hereinafter described.
- A designates the body of the bath-tub, and B is the roll-rim around the top edge of the tub. This roll-rim presents a continuously-curved broad surface around all the walls of
- the tub, at the top edge thereof. In cross- 30 section, Fig. 2, this rim is curved on a large radius outwardly from the walls of the tub, and at its outer edge said rim is curved inwardly underneath, as at b, the top curved portion c of the rim. 35
- C D are the pockets or depressions in the top curved surface of the rim B, and c' d are channels or grooves, which extend from the pockets or depressions and which merge into the inner surface of one of the walls of the tub. 40
- On its external surface the body of the tub has the pattern, consisting of the parallel bands or panels E E, which extend around the side and end walls of the tub.
- F G are the feet or legs. Each foot or leg 45 has a horizontal ridge f above the knobs g, and inclined corrugations h extend upward from this transverse ridge f. At the top of the foot is a series of leaves i and the scrolls or spirals j k, the spirals being on opposite 50 sides of the leaves.

What I claim is—

The design for a bath tub herein shown and described.

OSCAR MARSCHUETZ.
